CONTAINER OPENING KEY

Sidney J. Staples, Cape Elizabeth, Maine, assignor to American Can Company, New York, N. Y., a corporation of New Jersey

Application January 29, 1941, Serial No. 376,536

1 Claim. (Cl. 220—52)

This invention relates to key opening sheet metal containers and has particular reference to a punch and roll type opening key having a notched shank for uniformly rolling or winding off an outlined area from a wall of a container, to open the container and thereafter permit removal of its contents.

In certain respects, the instant invention constitutes an improvement upon the container opening keys illustrated and described in the John M. Hothersall United States Patents 2,017,061 and 2,017,062, issued October 15, 1935, and is especially an improvement in the construction of the shank of the key to insure even winding of a tearing area onto the shank.

The invention contemplates the provision of a container having a score or weakened line formed in one of its walls to define a removable area and a special form of key for removing such an area, the key having a sharpened lug capable of puncturing through the container wall at a definite point inside the score line when the key is in a horizontal position parallel with the container wall and the lug is pivotal about the key shank as the lug initially breaks through the container wall on the score line. Thereupon the lug is adaptable for lifting the initially severed edge without tilting so that rotation of the key tears loose the area along the score line uniformly in opposite directions, starting at the initially broken section and easily winding off the removable area, thus opening the container.

An object of the invention is the provision of an opening key for the removal of a scored or outlined area in the wall of the container, said opening key being provided with a spear or piercing lug which is adapted to puncture an opening at a predetermined location within the scored area when the key is placed in a horizontal position upon the container wall, the construction of the shank of the key permitting such positioning following which the key is operable when rotated on a parallel axis to break the metal of the container wall along the score line simultaneously in different directions so that the removable area may be rolled onto the shank of the key without twisting, thereby opening the container for the removal of its contents.

A further object of the invention is the provision of such an opening key for effectively removing a scored area from the wall of a container in which the flanged shank or body of the key is notched so that the axis of the key may be positioned parallel with the container wall during the first and subsequent turns of the key in

removing the scored area which thereby insures a straight roll over the seam edge of the container, whereupon continued turning of the key will wind off the removable area uniformly without twisting.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a container and a key embodying the present invention and illustrating the initial uniform tearing of the score line during the opening operation;

Fig. 2 is an enlarged fragmentary view in vertical section of a portion of the container illustrated in Fig. 1, and showing a piercing lug of the opening key inserted in the container wall;

Fig. 3 is an enlarged perspective view of the upper side of the opening key showing the notched out section of the shank;

Fig. 4 is a view similar to Fig. 3 showing the lower side of the key, as it would appear when the key is turned over; and

Fig. 5 is an enlarged transverse view in section as indicated by the line 5—5 (Fig. 3).

As a preferred embodiment of the invention there is shown in the drawing a sardine container 11 of the roll top variety, having a drawn body 12 and a top wall or cover 13 secured in any suitable manner as by a double seam 14. This top wall comprises a substantially flat panel which is countersunk beneath the upper edge of the double seam. Such a wall has a removable area 15 set off by a score line or weakened section 16 which is cut in the wall of the cover.

A plurality of defined key inserting positions or puncturing locations are marked in the removable area 15 of the cover wall as by detents or depressions 17 (Fig. 1). These detents are positioned a predetermined distance relative to the score line 16 of the cover and adjacent the opposite ends of the container. The base of such detents may be weakened to facilitate puncturing at either end just prior to an opening operation.

A punch and roll type container opening key 21 (Figs. 2, 3 and 4) is preferably formed by being blanked from a single piece of suitable sheet metal. Such a key comprises an elongated body or shank 22 having a finger engaging, oblong shaped head 23 formed at one end thereof and having a centrally disposed circular perforation 24 which permits the key to be strung on a cord or wire, or if desired, hung on a nail.

The shank section of the key has a rounded or arcuate mid-section 25 merging into two diverging side walls or flanges 26 and 27 defining an interposed longitudinal channel section of the key shank. The flanges 26 and 27 merge into a rounded front edge 28 at the forward end of the key shank. A laterally extending curved piercing lug or arm 31 is formed as an integral part of the flange or wall 26 adjacent the rounded front end of the shank (Figs. 2, 3 and 4). The piercing lug terminates in a sharpened point or spear as at 32 and the angular edge 33 thereof is preferably beveled or tapered to facilitate its easy insertion when puncturing the can wall.

The wall 26 of the shank 22 is preferably notched as at 34 adjacent the head of the key so that when the key is placed upon the can wall 13 prior to and at the start of an opening operation, there will be a bridge portion 35 connecting the channel section of the shank and the key head. In such position the key will be substantially parallel to the container wall (Figs. 1 and 2) being opened. The head 23 of the key is shown projecting outwardly over the double seam 14 in a convenient position for winding off the removable area of the container top wall.

In opening the container the sharpened point 32 of the key shank is first inserted by punching it into one of the detents 17 (Figs. 1 and 2) to engage the key 21 in a pivotal connection with the removable area 15. When in such a position the key may be turned in a clockwise direction (Fig. 1) so that the sharpened point 32 of the curved piercing lug 31 contacts the cover wall 13 directly beneath the weakened area constituting the score line 16. Further turning of the key, by reason of the curvature of the lug 31, causes the point 32 to initially break through the metal of the weakened section at the score line and thereafter sever it uniformly in opposite directions along the score line, as best illustrated in Fig. 1. By reason of the notch 34 the axis of the key will be parallel to the container wall at all times.

The length of the piercing lug 31 and the degree of its curvature determines the leverage of the key in its initial turning movement during an opening operation. For this reason the lug is

preferably made short and slightly curved to effect an easy break-through of the container wall.

The notched shank of the key permits straddling of the double seam 14 while the key is in a substantially parallel position on the cover wall 13 and operable by the overhanging head end, thus insuring a straight roll over the seam edge. The first turn of the key begins the winding of the removable area 15 onto the key shank in an even manner while the key is turned on a parallel axis as heretofore mentioned. Further turning of the key will complete the winding-off of the removable area onto the key shank in a uniform roll without twisting, thereby effecting an opening in the container wall for the withdrawal of the canned contents.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

A key for opening cans, consisting of a piece of metal blanked out to form a transverse handle by which the key may be rotated and having a shank portion bent into channel shape with longitudinal side walls spaced wider apart adjacent the handle, one of said walls at the wide part adjacent the handle being notched to provide a can seam bridge, the bottom of the notch being straight for the major portion of its width and the straight part being substantially parallel to and closely adjacent the longitudinal axis of the shank, the narrow outer end of said shank being provided with a laterally extending and curved piercing arm located on the same side of the shank as the notch for breaking through the can wall when the said shank is turned in opening the can along a weakened line, said notch maintaining the longitudinal axis of the shank parallel to the can wall during such turning action.

SIDNEY J. STAPLES.
